UNITED STATES PATENT OFFICE.

SUSAN BALL, OF ALBION, NEW YORK.

DESIGN FOR A WALL-POCKET.

SPECIFICATION forming part of Design No. 12,566, dated November 8, 1881.

Application filed April 7, 1879. Term of patent 7 years.

To all whom it may concern:

Be it known that I, SUSAN BALL, a resident of Albion, in the county of Orleans and State of New York, have invented and produced a 5 new and original Design for Wall-Pockets, of which the following is a specification, reference being had to the accompanying drawing, forming part thereof.

The figure of the drawing is a front view of 10 my improved wall-pocket, which fully illustrates my design.

Referring to the drawing, *a* is the outer or larger shield, which forms the front portion of the pocket. *b* is the rear portion of the pocket, 15 which is made flat, and which is adapted to rest against and be secured to the wall of a room.

The outer portion, *a*, of the pocket is curved, and is secured at its side and bottom edges, *c c'*, to the rear flat portion *b*. Upon the lower 20 central portion of shield *a* is a smaller shield, *d*, with its upper portion, *d'*, reserved for any inscription, figure, or picture which may be selected to be placed thereon. The lower portion, *d''*, of the shield *d* is divided into thirteen 25 spaces, representing bars. In the space between the upper edges of the outer shield, *a*, and inner or smaller shield, *d*, are arranged thirteen stars, in two triangular groups of six stars each with the thirteenth star centrally 30 located just above the two triangular groups. The upper stars of the two triangular groups are arranged in a line slightly curved and extending across the shield *a*. At the points *f*

of the shield *a* are secured the arrows *f'*, and at the upper and lower central points, *g*, of 35 shield *a* are the arrow-heads *g'*.

The leading features of my design are the outer and inner shields, with the thirteen stars and bars, and the space reserved in the inner shield for the reception of any tasty or appropriate inscription, figure, or picture. The other details—viz., the arrows and arrow-heads—might be varied without affecting the general appearance of my design.

I claim—

1. The design for wall-pockets herein shown and described, consisting, essentially, of the outer or larger shield, curved, as shown and described, to form a pocket, the inner or smaller shield located in the central lower portion of 50 the larger shield, the upper portion of which smaller shield is reserved for any inscription, figure, or picture, and the lower portion of which is divided into thirteen spaces or bars, and the thirteen stars arranged, as shown, between the 55 upper edges of the two shields.

2. The design for wall-pockets, consisting of the curved shield *a*, upon which is placed the shield *d*, with space *d'* and bars *d''*, the thirteen stars *e*, the arrows *f'*, and arrow-heads *g'*, located 60 at the points of the shield *a*, all arranged substantially as shown and described.

SUSAN BALL.
